UNITED STATES PATENT OFFICE

2,406,950

SELF-SQUEEZING MOP

Pearl M. Jackson, Chicago, Ill.

Application October 4, 1944, Serial No. 557,085

1 Claim. (Cl. 15—119)

1

This invention relates particularly to the head structure of mops of absorbent material and to mechanism incorporated in the structure of the mop head whereby liquids can be squeezed from the mopping material without the necessity of bringing the hands of the operator into contact with such material.

The main objects of this invention are to provide a simple, inexpensive and improved form of self-wringing mop; to provide a device of this kind having in addition to the usual handle an auxiliary handle by the manipulation of which the mop material may be efficiently squeezed; to provide a structure of this kind wherein the squeezing mechanism is held out of the way during normal mopping operations; to provide a mop structure of this kind wherein the movement of the squeezing member will gather up the absorbent body of mopping material into a compact mass for expressing liquid therefrom by a simple but powerful squeezing operation; and to provide a mop structure of this kind wherein the leverage of the squeezing mechanism may be readily adjusted to vary the squeezing pressure or accommodate a difference in the thickness of mopping material, due to wear or substitution thereof.

A specific embodiment of this invention is shown in the accompanying drawing in which:

Figure 1 is a perspective view of a simple form of mop structure according to this invention.

Fig. 2 is an elevation of the same as viewed from one end of the mop head with the presser member in its elevated or retracted position.

Fig. 3 is a similar elevation showing the cooperative relation of the mop head and presser member in the mop-squeezing position.

Fig. 4 is a similar view with the lever arms of the presser member adjusted to a different position for accommodating a thicker mass of absorbent material.

Fig. 5 is a fragmentary sectional detail taken on the line 5—5 of Fig. 2 through the trunnion connection between the mop head and presser member.

Fig. 6 is a similar sectional detail taken on the line 6—6 of Fig. 5.

Fig. 7 is an enlarged perspective view illustrating the manner in which the trunnion stud is flattened in cross section to permit the shifting of the presser lever arms from one pivotal aperture to another to adjust the leverage of those arms.

Fig. 8 illustrates the relation of the flattened trunnion with respect to one of the pivot aper-

2

tures and the slot along which the trunnion may be shifted to another aperture.

In the form shown in the drawing, the mop head 1 is a rectangular block having an elongated handle 2 connected thereto in suitable disposition for floor mopping operations. A body 3 of absorbent material is attached to the mop head 1. As shown this material may be a mass of depending strands sewed to a sheet 4 of cloth or the like which embraces the mop head 1 and is securely fastened by lacing 5.

A second block 6 approximating in size the block 1 is attached to the block 1 by means of a pair of flat lever arms 7 which are securely fastened to the ends of the block 6 and extend approximately at right-angles to the main plane of that block. The arms 7 are each provided with a pair of pivot apertures 8 and 9 spaced apart along the lever arm 7 and since the bracket members which embody the lever arms 7 are exactly alike, the pivot apertures 8 of the two levers will be in axial alignment, as will be apertures 9.

Trunnions are mounted on the opposite ends of the block 1 in axial alignment with each other 25 for connection with the lever arms 7 and comprise studs 10 whose sectional contour is that of a segment of a circle of a diameter to fit the pivot apertures 8 and 9 but flattened at opposite sides to reduce one diameter thereof to a width

30 corresponding to a narrow slot 11 which connects the apertures 8 and 9. The stud 10 is provided with a central aperture 12 to receive the attaching screw 13 and with prongs 14 which are driven into the body of block 1 to prevent the trunnion

35 stud from rotating. Thus the flat surfaces of the studs at opposite ends of the head 1 will always remain in proper relation to permit of adjusting the trunnions 10 from one pivot aperture to another. These trunnion flats are preferably disposed in planes approximately parallel to the plane of the bottom of the head 1 so that the adjustment of the leverage of the arms 7 can be effected only when the squeezing member 6 is in an intermediate position between its operation position, shown in Figs. 3 and 4, and its retracted position shown in Fig. 2. A washer

40 45 50 55 50 which is preferably integral with the stud 10, overlays the margins of the pivot apertures 8 and 9 and slot 11 and confines the lever arms to their proper relation to the studs 10.

The presser block 6 is provided with a short auxiliary handle 16 whereby it is swung on its pivotal connection with the head 1 and it is also provided with a spring clip 17 positioned for latching engagement with the handle 2 to hold

the presser block 6 in its normal retracted position while the mop is in use.

In operation when the presser block is swung from the position in which it is shown in Fig. 2 to the positions in which it is shown in Figs. 3 and 4, it comes into contact with the strands of the mop 3 and folds them against the head block 1 so that they may be effectively squeezed while the hands of the operator are grasping the handles 2 and 16, wherefor it is not necessary for the operator to bring his hands into contact with the absorbent material of the mop.

Preferably in a mop of this kind, the strands of material 3 which are at the right in Fig. 2 are made longer than those at the left side so that the mop material is effectively gathered up for pressure between the two heads as shown in Figs. 3 and 4. With the studs disposed as shown, the adjustment of the presser from one pivotal axis to another, can be readily accomplished when the block 6 is at the midpoint of its arc of movement, by a simple movement in a radial direction.

Although but one specific embodiment is herein shown and described, it will be understood that details of the structure shown may be altered or omitted without departing from the spirit of

the invention as defined by the following claim.

I claim:

A mop comprising a head member having a handle, a body of absorbent material dependently attached to said head member, a presser member having a pressing face for squeezing the absorbent material against said head, a pair of longitudinally disposed and axially aligned trunnions projecting from opposite ends of said head member, parallel lever arms rigidly attached to opposite ends of said presser member, being disposed transversely to the pressing face thereof and having spaced bearing apertures to rotatably engage said trunnions at selective distances from said pressing face, and a handle on said presser member, said trunnions having circular cross sectional contours correspondingly flattened at opposite sides in substantially parallel relation to said pressing face, and said lever arms each having a contracted slot connecting its said bearing apertures and proportioned to permit the passage of the respective trunnion from one bearing aperture to another only when said slot registers with the flattened sides of said trunnions.
